UNITED STATES PATENT OFFICE.

JAMES FRASER LISTER AND HORACE WILL SMALLWOOD, OF BIRMINGHAM, ENGLAND,
ASSIGNORS TO VERITYS LIMITED, OF LONDON, ENGLAND, A REGISTERED BRITISH
COMPANY.

AUTOMATICALLY OSCILLATING ELECTRIC FAN.

Application filed December 7, 1925, Serial No. 73,744, and in Great Britain December 13, 1924.

The invention relates to an automatically oscillating electric fan of the kind in which the fan oscillates in two planes simultaneously from the drive of the fan wheel 5 spindle through a speed reducing gear which drives a crank arm or plate and through an oscillating mechanism provided between the crank arm or plate and a fixed point on a stationary fan support or the surface to 10 which the fan is applied, providing a fixed abutment from which the oscillations are forced. A combined motor casing and fan body has been mounted to rock on trunnions of a frame which itself can rock on an axis 15 at right-angles to the trunnions and the speed of the fan wheel shaft has been geared down to very slowly drive a crank arm or plate.

The invention provides in this kind of fan 20 simple oscillating mechanism very inexpensive to produce and fit, very smooth and efficient in action and distinctive by a telescoping member applied between the crank arm or plate and a stationary abutment through 25 which the combined oscillations are forced from the drive of the fan wheel spindle. One part of the telescoping member is a sleeve and the other part is a rod slidably and rotatably engaging the sleeve and one 30 of these parts, preferably the sleeve, is fixed to the stationary mounting of the fan or other abutment while the other part preferably the rod suitably connects with the crank arm or plate. The telescoping member 35 therefore comprises two parts aforesaid one to be held stationary and the other to revolve and slide in the stationary part, the feature of the part held stationary being that it is immovable transversely or side 40 ways and becomes the operative surface of the fixed abutment.

Three forms of the invention are represented by the accompanying drawings each embodying the same essential feature 45 namely the use of the telescoping member aforesaid between the crank arm or plate and the fixed abutment.

Fig. 1 is a side sectional elevation of a 50 ceiling fan embodying the features of the present invention.

Fig. 2 is an elevation of Fig. 1 at right angles.

Fig. 3 is a side sectional elevation of a 55 table or pedestal fan.

Fig. 4 is a rear end view of a portion of Fig. 3.

Fig. 5 is a detail section of Fig. 3 on the dotted lines A. B.

Fig. 6 is a side sectional elevation of a 60 further form of table or pedestal fan.

Fig. 7 is a rear end view of a part of Fig. 6.

In all the figures of the drawings similar letters of reference are used to indicate 65 corresponding parts.

With particular reference to Figs. 1 and 2 the combined motor casing and fan body *a* through which the fan wheel spindle *c* passes and within which it revolves is mounted by opposite trunnions *a*², *a*³, to rock 70 within a ring *d* which in turn is mounted upon opposite trunnions *d*², *d*³, to rock upon a bifurcated frame *e* rigidly hanging from a ceiling connection *f* this frame being at all times a fixture. Said combined casing 75 and body and fan wheel shaft, can therefore oscillate in two planes at right-angles, the trunnions *a*², *a*³, and *d*², *d*³, being at right-angles. At the rear the casing and body provides an extension *a*⁴ to which the greater part of the speed reducing gear is 80 fitted. The whole of the parts aforesaid are substantially balanced in the ordinary way.

This gear comprises a small worm *g* axial 85 of the fan wheel spindle *c* and continuously driven thereby, a worm wheel *h* driven by the worm and mounted on a small shaft *h*² upon which is also mounted a second worm *i* adapted to drive a worm wheel *j* 90 mounted upon a crank shaft *j*² to which is attached a crank arm *k*, said attachment being by a safety friction clutch *l* which operates only to let the crank shaft revolve from the gear when the oscillations of the 95 fan are forcibly accidentally stopped.

All the features hereinbefore particularly described have been previously proposed in a fan of the kind to which the invention relates.

The invention is the use between the crank arm *h* or its equivalent and the bifurcated frame *e*, or other equivalent stationary abutment, of a telescoping member *x* comprising a sleeve *x*² and a rod *x*³ which engage both 100 slidably and rotatably. The sleeve *x*² of the telescoping member is vertically formed in the crown *e*² of the stationary bifurcated

frame α and forms the abutment surface for forcing the oscillations while the rod α^3 slides and revolves within the sleeve a working fit and at its lower end α^4 is jointedly connected to the outer end k^2 of the crank arm k which outer end may turn slightly about the axis of the crank arm. The manner of joining the lower end α^4 of the rod α^3 to the crank arm end k^2 is clearly represented by the drawings.

It will be clear from the foregoing that the telescoping member α forms a simple and most efficient oscillating mechanism coupling the crank arm with a stationary abutment and that when the fan wheel spindle is driving the crank arm the telescoping member forces the whole fan to oscillate on the trunnions in combined planes about the telescoping member as a lateral or sideways immovable part, the rod α^3 in the oscillations sliding and revolving within the fixed sleeve α^2 .

With particular reference to Figs. 3, 4 and 5 the sleeve α^2 of the telescoping member α is rigidly carried upon the upper end of a peg e^2 rigidly rising from a base e forming the support for the fan. The sleeve is horizontally disposed. Said peg e^2 also provides a pivot for a bifurcated frame d within whose branches the combined motor casing and fan body a is mounted to rock on opposite trunnions a^2 . The casing can rock on the frame d in a vertical plane and the frame d can rock on the peg e^2 in a horizontal plane. The frame d seats itself on a thrust ball bearing e^3 of the base e .

The rod α^3 of the telescoping member α slidably and revolvably engages the sleeve α^2 and at its outer end α^4 jointedly connects with the outer end k^2 of the crank arm k which outer end k^2 has a very slight axial movement on the crank arm.

The speed reducing gear from the fan wheel spindle c to the crank arm k is substantially as before described that is to say the worm g , worm wheel h , worm i and worm wheel j driving the small crank shaft j^2 .

The safety friction clutch l is provided between the crank shaft j^2 and the crank arm k .

When the crank arm is driven from the fan wheel spindle the rod α^3 of the telescoping member α will revolve and slide within the sleeve α^2 which being the surface of an immovable abutment will force combined oscillations of the fan about two axes at right-angles.

With particular reference to Figs. 6 and 7 a crank plate k is substituted for the crank arm in the previous forms and the rod α^3 of the telescoping member α is rigidly applied thereto as a crank pin. The other part of the telescoping member α is the sleeve α^2 which is mounted to universally rock in a housing m of a rigidly built arm n fixed to

project immovably from the upper end of the peg e^2 of the supporting base e of the fan. Except that the sleeve may rock in the housing it is otherwise immovable that is to say it is laterally immovable and forms the operative surface of the fixed lateral abutment from which the combined oscillations are forced consequent upon the revolution of the crank plate. The rod α^3 both slides and revolves in the sleeve from the revolution of the crank plate k .

Except as just described this form of oscillating fan is the same as the form Figs. 3 to 5.

The bifurcated frame d rocks on the peg e^2 in a horizontal plane and the combined motor casing and fan body a rocks upon the frame d in the vertical plane while the speed reducing gear from the fan wheel spindle c comprises the worm g on the fan wheel spindle, the worm wheel h and spur pinions i^2 and j^3 driving the crank plate shaft j^2 on which the crank plate k is mounted.

Having now described our invention, what we claim and desire to secure by Letters Patent is:—

1. An electrically driven oscillating fan combining a stationary support for the fan, a frame mounted to rock upon said support in one direction only, a combined motor casing and fan body arranged to rock upon the frame at right-angles to the rocking of the frame itself, a fan shaft rotatable in the casing and body, a crank rotated by the fan wheel shaft through a gearing, and a telescoping member comprising a rod and a sleeve slidably and revolvably engaging each other operative between the crank and the stationary support for the fan to force combined oscillations of the fan from the rotation of the fan wheel spindle, substantially as described.

2. An electrically driven oscillating fan combining a stationary support for the fan, a frame mounted to rock upon said support in one direction only, a combined motor casing and fan body arranged to rock upon the frame at right-angles to the rocking of the frame itself, a fan shaft rotatable in the casing and body, a crank arm rotated from the fan wheel shaft through a gearing and a telescoping member comprising a rod pivoted to the crank and a fixed sleeve carried by the support and with which the rod slidably and revolvably engages in a manner forcing combined oscillations of the fan from the rotation of the fan wheel spindle, substantially as described.

3. An electrically driven oscillating fan combining a stationary support for the fan, a frame mounted to rock upon said support in one direction only, a combined motor casing and fan body arranged to rock upon the frame at right-angles to the rocking of the frame itself, a fan shaft rotatable in

the casing and body, a crank arm rotated from the fan wheel shaft through a gearing and which is mounted upon its shaft by a safety friction clutch, and a telescoping member comprising a rod pivoted to the crank and a fixed sleeve carried by the support and which rod slidably and revolubly engages in a manner forcing combined oscillations of the fan from the rotation of the fan wheel spindle, substantially as described.

4. An electrically driven oscillating fan combining a stationary support for the fan, a frame mounted to rock upon said support in one direction only, a combined motor casing and fan body arranged to rock upon the frame at right-angles to the rocking of the frame itself, a fan shaft rotatable in the casing and body, a crank arm rotated from the fan wheel shaft through a gearing and whose outer end may turn slightly about the axis of the crank arm and a telescoping member comprising a rod pivoted to the crank and a fixed sleeve carried by the support and which the rod slidably and revolubly

engages in a manner forcing combined oscillations of the fan from the rotation of the fan wheel spindle, substantially as described.

5. An electrically driven oscillating fan combining a bifurcated stationary support to hang from the ceiling, a ring mounted to rock upon opposite trunnions of the bifurcated support a combined motor casing and fan body arranged to rock within the ring at right-angles, a fan shaft rotatable in the casing and body, a crank arm rotated by the fan wheel shaft through a gearing, a telescopic connection between the support and crank arm and consisting of a rod pivoted to the outer end of the crank arm and a sleeve formed as a fixed part of the bifurcated stationary support to be engaged by the rod with a slidable and revoluble engagement, substantially as described.

In testimony whereof we have hereunto set our hand.

JAMES FRASER LISTER.
HORACE WILL SMALLWOOD.
